(57) **CLAIM**

The ornamental design for a portable lamp, as shown and described.

DESCRIPTION

1. Portable lamp

2. Portable lamp

Fig. 1.1 is a top and side perspective view of the portable lamp showing my new design, according to a first embodiment;

Fig. 1.2 is a side elevation view thereof;

Fig. 1.3 is a top plan view thereof;

Fig. 1.4 is a side perspective view thereof;

Fig. 1.5 is another side perspective view showing the lamp in an illuminated state, thereof;

Fig. 1.6 is another side perspective view showing the lamp in an extended state;

Fig. 2.1 is a top and side perspective view of the portable lamp, according to a second embodiment;

Fig. 2.2 is a side elevation view thereof;

Fig. 2.3 is a top plan view thereof;

Fig. 2.4 is a side perspective view thereof;

Fig. 2.5 is another side perspective view showing the lamp in an illuminated state, thereof; and

Fig. 2.6 is another side perspective view showing the lamp in an extended state.

Portions of the portable lamp shown in broken lines form no part of the claimed design.
